UNITED STATES PATENT OFFICE.

ALEXANDER FULLARTON GILL, OF JOHANNESBURG, TRANSVAAL, SOUTH AFRICA.

GATE VALVE.

Application filed December 17, 1924, Serial No. 756,509, and in South Africa December 31, 1923.

The present invention relates to gate valves; the purpose being to provide an improved construction suitable for use in a pipe line and adapted to avoid accumulation 5 of solid matter under the gate.

The accompanying drawing shows a valve constructed according to the invention and sectioned longitudinally.

2 is the valve casing comprising the inlet 10 passage 3, the outlet passage 4, the gate seat 5 and the abutment 6 against which the gate bears when seated.

The gate 7 is of the usual downwardly tapered form to wedge between the seat 5 15 and the abutment 6. It is raised and lowered by means of the spindle 8.

The gate travels in a recess 9 in the body, which recess in most gate valves continues 20 uninterruptedly around the lower part of the casing. The lower portion of said recess is consequently below the level of the inlet and outlet passages, with the result that when liquid containing solid matter is passed 25 through the valve, some of the solid matter is liable to settle in the lower part of the recess and hinder the seating of the gate.

The present invention overcomes this difficulty by raising the seat 7 and the recess 9 30 relatively to the inlet and outlet passages so as to bring the lowest part 10 of the seat substantially not lower than the extremities 35 of the inlet and outlet passages, and by providing a substantially level outlet 11 from the lowest point of the seat and the recess.

33 A-B indicates the axial line of the valve, being the line joining the centres A and B of the outer ends of the passages 3 and 4, which axial line is horizontal when the valve is in its intended normal position. The 40 flanges 12 for fixing the valve are normal to said axis A-B; or if screw threads or other fixing means are employed, they are equivalently formed to position the valve co-axially with a pipe or other part to which the valve 45 is fixed.

Assuming the seat 5 to be of the usual circular form, its centre C is displaced from 50 the axis A-B, in the direction in which the valve opens, by a distance about equal to the width of the valve seat. The inlet passage 3 correspondingly slopes upwards from its outer end to the seat 5. The outlet passage 55 as a whole similarly slopes down to its outer end, but the lower part of said outlet passage

is cut away at 11, so as to eliminate the lower 55 part of the abutment 6 and to provide a channel the lower surface 13 of which forms a continuation of the lower surface of the recess 9 and is substantially parallel with the axis A-B, or in other words, level. As the 60 result, any solid matter which drops into the recess 9 is readily scoured away along the surface 13.

The under surface 14 of the gate may be inclined as shown to facilitate the seating of 65 the valve should solid matter be present under it; and the abutment 6 may be cut away as indicated at 15 to reduce friction.

It will be seen that when the valve de- 70 scribed is inserted into a pipe line, the upward slope of the inlet and outlet passages towards the seat 5 and the raising of the seat 5 so that its centre point 6 is above the axis A-B, bring the lower surface 10 of the gate recess 9 into line with the lower surfaces 75 of the adjacent pipes. Also the cutting away of the lower surface of the sloped outlet passage 4 provides a free outlet 11 from the lower part 10 of the gate recess 9.

There is accordingly no pocket into which 80 the solid matter can settle; solid matter which tends to settle in the gate recess 9 being scoured therefrom along the level surface 13 as easily as it is scoured along the lower surface 10 of the pipe line, of which 85 the surface 13 in fact forms a continuation. If the passages 3, 4 were not sloped upwards and the seat 5 not raised, the lower surface 10 of the gate recess 9 could be brought into 90 line with the pipe line at the outlet end of the valve only by lowering the outlet 4 in relation to the inlet 3 to the same extent that the seat 5 is raised in the present case. Such 95 constructions are known, but have the obvious disadvantage of necessitating the pipe line attached to the outlet end of the valve being disaligned with and lower than the pipe line attached to the inlet end of the valve.

I claim:

1. A gate valve, having a casing including 100 alined inlet and outlet passages and also including an annular seat, and a gate slidably mounted on said seat substantially perpendicular to said passages; the inlet and outlet passages sloping inwardly and upwardly in opposite directions from their outer ends toward said seat, and the lower 105

part of the outlet passage being cut away longitudinally thereof and of the casing to provide a level-bottomed channel leading from the seat to the outer end of that passage.

2. A gate valve having a casing including inlet and outlet passages the extremities of which are centred on a common axis, the casing providing means for fixing the valve 10 co-axially with other bodies, the casing also providing an annular seat substantially perpendicular to said axis, the centre of said seat being displaced from said axis in the direction of opening of the gate by a distance 15 substantially equal to the width of the valve seat, the inlet and outlet passages sloping from their extremities towards the seat, and

the lower part of the outlet passage being cut away longitudinally thereof and of the casing.

3. A gate valve, comprising a sliding valve member; and a casing providing a recess into which the valve member is moved to close, and also providing inlet and outlet passages the outer ends of which are centered on a common axis, such passages sloping inwardly and upwardly in opposite directions from their said outer ends toward said recess, the lowermost portion of the internal surface of the outlet passage being parallel with the aforesaid axis and in unbroken continuation with the lowermost surface of the gate recess.

In testimony whereof I affix my signature.
ALEXANDER FULLARTON GILL.
